ALARM DEVICE

Lue V. Gregson, Seattle, Wash.

Application March 18, 1933, Serial No. 661,530

15 Claims. (Cl. 116—92)

This invention relates to improvements in alarm devices, and aims primarily to provide a novel and improved two-way or double action alarm device especially designed and adaptable for use upon doors, windows, shutters, or the like, whereby opening of the same from the outside will actuate the device and thus sound an alarm.

Contemplated by the present invention is a two-way or double action alarm device adapted to be attached to a surface at a door, window, shutter, or the like, and embodying a tripping or kick-off lever having a neutral position, wherefrom such lever is adapted to be moved in either direction for effecting actuation of the alarm mechanism, as for example, upon turning of the outer door knob, or opening from the outside of the window sashes, shutter, or the like.

With the foregoing in view the invention essentially resides and is more particularly concerned in the provision of a two-way or double action alarm device for use upon a door, window, shutter, or the like; which in its preferred embodiment is characterized by the employment of a casing adaptable for attachment to the door, window casing, or shutter, in any desired or selected position thereon; a spring actuated mechanism disposed within said casing including an escapement, clapper and alarm bell; means for locking said escapement and clapper in an inactive or inoperative position; a two-way or double action alarm release dog connected to said escapement and clapper; a two-way or double action tripping or kick-off lever adapted when in a neutral position to selectively engage or contact either side of said alarm release dog for locking the escapement and clapper independently of the first mentioned locking means; and actuating means for said tripping lever adapted to be attached to the inner door knob, or inner side of the window sashes for effecting tripping of said lever and release of said dog and the sounding of an alarm, when and in the event said first mentioned locking means is unlocked and the outer door knob is turned in either direction, or either of the window sashes are opened from the outside; all of which are important elements and features of the invention and are to be correlated in the broad aim of enhancing the efficiency of the alarm device for the uses and purposes for which the same is primarily designed and intended.

The above, and additional objects which will hereinafter be more specifically treated are attained by such means as are shown in the accom-

panying drawings, described in the following specification and then more clearly pointed out in the claims, which are appended hereto and form part of this application.

With reference to the drawings, in which there are illustrated several embodiments of the invention, and throughout the several views of which like characters of reference designate similar parts:

Figure 1 is a vertical longitudinal section of an alarm device comprehended by the present invention, as it would appear when operatively attached to the inner side of a door and to the inside knob of a mortise lock of the non-swivel spindle type, said section being taken through line 1—1 of Fig. 2, with the alarm mechanism illustrated in a locked non-ringing position.

Fig. 2 is a horizontal longitudinal section of the same taken through line 2—2 of Fig. 1.

Fig. 3 is a section similar to Fig. 1, with the alarm mechanism illustrated in an unlocked ringing position.

Fig. 4 is a fragmentary vertical section taken in the plane of Fig. 1 and illustrating the tripping lever and escapement in a reversed locked or non-ringing position to that shown in Fig. 1.

Fig. 5 is a fragmentary elevation of the inner side of a door and its inner door knob equipped with the alarm device of the present invention, as it would appear when actuated or in a ringing position.

Fig. 6 is a similar elevation of a door equipped with a slightly modified type of alarm device.

Fig. 7 is a horizontal section taken through line 7—7 of Fig. 6.

Fig. 8 is a fragmentary vertical transverse section taken through line 8—8 of Fig. 7.

Fig. 9 is a fragmentary elevation of a window and its correlated casing equipped with another slightly modified type of alarm device, as it would appear with the window closed.

Fig. 10 is a vertical transverse section of the same taken through line 10—10 of Fig. 9 with the window sashes illustrated in a ventilating or open position and in readiness to trip the alarm mechanism upon further opening movement, and

Fig. 11 is a fragmentary horizontal section taken through line 11—11 of Fig. 10.

Beginning now the more detailed description of the invention by reference to the accompanying drawings, and referring now more particularly to Figs. 1 to 5, inclusive, wherein the numeral 12 designates a door, 13 the door casing, 14 a mortise knob lock of well known type having a non-swivel spindle 15 and inside and outside knobs 110

16 and 17, which are fixedly secured to the inner and outer ends, respectively, of said spindle 15 by screws 18 and 19, see Fig. 2.

Mounted upon the inner side of the door 12 is the alarm device evolved by the present invention and herein generally designated by the numeral 20, said device in the form disclosed in Figs. 1 to 5, inclusive, embodying a relatively shallow or short cylindrical casing 21 having an open rear end adapted to normally abut the door 12 and to be closed thereby, substantially in the manner shown in Fig. 2. In the present disclosure the casing 21 is adapted to be fixedly secured, as by screws 22, to the door 12 in contiguous spaced parallel relation to its inner knob 16, this for a purpose which will shortly be made more apparent.

Disposed within the casing 21 and rigidly secured, as by screws 23, to the inner face of the front or outer end wall of said casing is an alarm mechanism generally designated by the numeral 24 comprising front and rear frame plates 25 and 26, which are rigidly interconnected in spaced parallel relation by screws 27 and spacer sleeves 28. Journalled at its terminals within the lower left hand portions of the frame plates 25 and 26 is a transversely disposed spring winding arbor or spindle 29, upon which is mounted an expanding spiral or clock spring 30 with its inner end fixedly secured thereto, while its outer end is anchored to a transversely disposed pin 31 having its terminal portions seating within the frame plates 25 and 26. The arbor or spindle 29 at its forward end is adapted to project through the front wall of the casing 21 and is provided thereat with a winding key 32 for effecting rapid and ready winding of the spring 30 in an obvious manner.

The numeral 33 designates a train of gearing interposed between and mounted within the frame plates 25 and 26 in a well known manner, which gear train is adapted to interconnect the spring arbor 29 with a transversely disposed escapement arbor or spindle 34 for imparting rotative movement thereto, said last mentioned arbor 34 having its terminals journalled within the upper left hand portions of the frame plates 25 and 26 and having an escapement or regulating wheel 35 rigidly mounted thereon adapted to be alternately engaged by the pallets 36 of a rocking anchor member 37 rigidly connected to a transversely disposed shaft 38 mounted for rocking movement within the frame plates 25 and 26 in superimposed spaced parallel relation to the escapement arbor 34.

Fixedly secured to the shaft 38 and extending upwardly and inwardly therefrom is a vibratory arm 39 having a clapper or hammer 40 upon its inner free end, which hammer is adapted to contact or strike a bell 41 interposed between the frame plates 25 and 26, and which is operatively mounted in any well known manner upon said frame plate 26. Similarly secured to the shaft 38 and extending upwardly and inwardly therefrom is a rearwardly offset locking arm 42, the inner free terminal of which is adapted to be engaged upon its underside by a locking or shut-off member 43 fixedly secured to a transversely disposed shaft 44 journalled within the frame plates 25 and 26 and adapted at its forward end to project through the front wall of the casing 21, whereat it is provided with a knurled thumb knob 45 for effecting rapid and ready locking and unlocking of the arm 42. A stop pin 46 projecting from the inner face of the frame plate 26

is provided to limit rocking movement of the locking member 43 in a counter-clockwise direction, as shown in Figs. 1 and 4, this in order to insure of positive locking engagement being obtained between the arm 42 and member 43, at which time the clapper or hammer 40 is inactive, as will be manifest and apparent by referring to Figs. 1 and 4.

Fixedly secured to the shaft 38 adjacent the inner face of the frame plate 25 in spaced parallel relation thereto is an inwardly and downwardly inclined two-way or double action alarm release dog 47, the sides of which, at the inner free end thereof, see Figs. 1 and 4, are adapted to be selectively engaged or contacted by the inner end of a two-way or double action tripping or kick-off lever 48, when the latter is in a neutral or non-active position, said lever being pivotally mounted, as at 49, upon the inner face of said frame plate 25 and being rearwardly offset, as shown at 50 in Fig. 2, to project through a circumferential slot 51 formed in the cylindrical walls of the casing 21, from which casing said lever 48 extends for approximately one-half its length for a purpose which will now be described.

The numeral 52 designates a substantially U-shaped actuating member for the tripping lever 48 adapted to be clamped, as by a clamping screw 53, to the shank of the inner door knob 16, with its legs extending tangentially therefrom in slightly convergent relation, see Figs. 1, 3 and 5, said legs having longitudinally disposed elongated slots 54 formed therein intermediately of the clamping screw 53 and their outwardly bent or flaring terminals 55, the purpose of said slots and flaring terminals being hereinafter made more apparent. When the tripping lever 48 is in a neutral or inactive position, the outer end of said lever is adapted to normally lie or be interposed between the legs of the actuating member 52, substantially in the manner illustrated in Fig. 1, so that any turning movement of the outer door knob 17 in either direction will cause one or the other of the said legs to contact or abut said lever and move same from its neutral position. To materially increase the clamping action or frictional engagement of the member 52 upon the shank of the inner door knob 16, a longitudinal strip or tongue 56 is cut from the material of said member, substantially midway its length, and such strip is bent inwardly in arcuate formation to conform to the cylindrical contour of said shank and to normally contact or abut the latter, so that said shank is substantially encircled or embraced by the member 52, all as more clearly shown in Figs. 1 and 3.

In initiating the use of the present alarm device 20 the casing 21 thereof is installed upon the inner side of the door 12 in proximity to the inner door knob 16, either at the left hand side of said knob, as shown in Figs. 1, 3 and 5, or above or below such knob, as is found most convenient or most expedient for the particular installation, following which, with the tripping lever 48 in a neutral or inactive position the actuating member 52 of the device 20 is clamped to the shank of the inner door knob 16 in an obvious manner, with its legs projecting therefrom towards the casing 21, whereby the outer terminal portion of the tripping lever 48 is interposed between the outer terminal portions of said legs, substantially as illustrated in Fig. 1. With the alarm device 20 installed, as above set forth, the same is set to sound an alarm in the following described manner. The thumb knob 45 is manipulated to un-

lock the locking arm 42, as shown in Fig. 3, but, as the alarm release dog 47 is in engagement with the tripping or kick-off lever 48, the latter being in its neutral position, the spring actuated mechanism associated with said dog including the escapement and clapper remain locked or inactive. With the alarm device 20 set to operate, as above set forth, turning of the outer door knob 17, in either direction, will cause or impart similar turning movement to the inner door knob 16 and thereby an oscillation of the actuating member 52, which in turn effects oscillation of the tripping lever 48 from its neutral or central position and its consequent disengagement from or release of the dog 47 to effect actuation of the alarm mechanism and the ringing of the bell 41 in a well known manner. During the above described oscillation of the actuating member 52 and the tripping lever 48, it is to be noted that the outer end of the latter is adapted to enter and extend through one or the other of the slots 54 of the member 52, depending upon the direction of oscillation of said member, and it is also to be noted that the curved or flaring outer terminal 25 of the leg opposite to that entered by the tripping lever 48 is in abutment with the adjacent edge of the same, this for the purpose of maintaining said tripping lever 48 and the member 52 in operative relation at all times. After sounding an alarm the device 20 may be again reset or rendered inactive by moving or returning the tripping lever 48 and its correlated actuating member 52 to their neutral or central positions, as shown in Fig. 1, or said device may be rendered entirely inactive by manipulating the thumb knob 45 and thereby causing the locking member 43 to engage the locking arm 42, as shown in Figs. 1 and 4.

While the device 20 has been primarily designed for use as a burglar alarm I desire to have it understood that the same may be employed as a fire alarm, or as a substitute for alarm clocks, in hotels, apartment houses, rooming houses, and the like, and in the event of fire or to awaken the occupants for any other reason the operator passes rapidly along the halls or corridors turning the knob of each door and thus setting off the alarm in each instance.

In Figs. 6, 7 and 8, inclusive, the numeral 12a designates a door, 13a the door frame and 14a the door lock, all of which are of well known construction. The numeral 20a generally designates an alarm device of slightly modified type adapted to be attached to or installed upon the inside of the door 12a adjacent the door frame 13a, but, in any selected or desired position thereon relative to and independently of the door lock 14a, accordingly the alarm device 20a is attached to the door 12a in such a manner that its periphery is in abutment therewith, so that said device projects therefrom in perpendicular relation thereto, as shown in Figs. 6 and 7.

The numeral 21a designates the casing of the alarm device 20a having a flattened portion 21b on its periphery for abutment with the door 12a, said portion having lugs 21c wherethrough screws 21d extend for fixedly securing the casing 21a to the door 12a. The casing 21a is provided with an open upper end adapted to be normally closed by a cover 21e snugly fitting within said open upper end and is fixedly secured therein by screws 21f.

The alarm device 20a is provided with alarm mechanism, not shown, identical to that hereinbefore described for the alarm device 20, which mechanism is fixedly secured within the casing

21a, as by screws 23a, and is wound by a winding key 32a, locked by a thumb knob 45a, and tripped or kicked-off by a tripping lever 48a, which latter extends, through a slot 51a, from the casing 21a in the same manner as the lever 48 extends from its correlated casing 20, and at its outer end is adapted to engage, when in its neutral or inactive position, a resilient actuating member 52a fixedly secured, as by screws 52b, to the door frame 13a, wherfrom it projects perpendicularly as shown more clearly in Fig. 8, and adjacent its outer end is upwardly offset to provide a catch or lug 52c for engaging the outer end of the tripping lever 48a when the same is in a neutral position as above described.

With the door 12a closed and the tripping lever 48a in its neutral position and its outer end in engagement with the catch 52c, as shown in Figs. 7 and 8, the alarm device 20a is set by manipulating the thumb knob 45a to release or unlock the mechanism associated therewith, so that upon initial opening movement of the door 12a the tripping lever 48a will be oscillated to release and set off the alarm mechanism, by reason of the fact that its outer end is restrainingly engaged by the catch 52c, and remains so engaged until the tripping lever 48a reaches the end of its slot 51a, at which time the outer end of said lever disengages itself from said catch, it being here understood that the slightest opening movement of the door 12a is sufficient to actuate or set-off the alarm mechanism. To reset the alarm device 20a the tripping lever 48a is returned or moved to its neutral position and the door 12a closed, at which time the resilient actuating member 52a is flexed downwardly to permit passage of the outer end of the tripping lever 48a over the catch 52c to again effect engagement therewith. To render the alarm device 20a inactive the thumb knob 45a is manipulated to lock the alarm mechanism associated therewith.

In Figs. 9 to 11, inclusive, the numeral 57 generally designates a window, 58 the window casing, 59 the lower sash and 60 the upper sash thereof, all of which are of well known construction.

Mounted upon the face of the window casing 58, at a point thereon slightly above the upper end of the lower sash 59 when the same is closed, is an alarm device generally designated by the numeral 20' having a casing 21' fixedly secured to said window casing by screws 22'. The alarm device 20' is provided with alarm mechanism, not shown, identical to that hereinbefore described for the alarm device 20, which mechanism is fixedly secured within the casing 21', as by screws 23', and is wound by a winding key 32', locked by a thumb knob 45', and tripped or kicked-off by a tripping lever 48', which latter extends, through a slot 51', from the casing 21', in the identical manner herein shown and described for the lever 48. In this type of installation, the alarm device 20' is mounted upon the window casing 58, so that its tripping lever 48' projects in the direction of the window sashes 59 and 60, see Fig. 9, whereby opening movement of such sashes is utilized for effecting actuation of said alarm device 20', and for this purpose the lower window sash 59 is provided adjacent the casing 58 with a T-headed alarm actuating pin 61 threadedly engaged at its inner end within said sash to project perpendicularly therefrom at a point thereon near the upper end thereof, the T-head of said pin being provided to effect rapid and ready placement of the pin in the sash 59 without the necessity of using a screw driver or other tool. Similarly, the upper

145

150

window sash 60 is provided adjacent the casing 58 with an alarm actuating pin 62 threadedly engaged at its upper inner end within said sash substantially in vertically aligned relation with the 5 T-headed pin 61, see Fig. 9, said pin 62 being threadedly engaged in said sash 60 adjacent its lower end and being adapted to extend perpendicularly therefrom to a point beyond the plane of the face of the casing 58, whereat it is bent downwardly at right angles and at its lower end is bent outwardly at right angles, thereby forming a pin of substantially Z-shaped formation, which latter permits rapid and ready placement of the pin 62 in its sash 60 without the use of any tools 10 and also permits of opening movements of the window sashes 59 and 60 to ventilating positions and tripping of the alarm device 20' by either sash, without such pin fouling or conflicting in any way with the lower sash 59.

With the window sashes 59 and 60 in a closed 20 position and the tripping lever 48' in its neutral or central position, as shown in Fig. 9, the alarm device 20' is set by manipulating the thumb knob 45' to release or unlock the mechanism associated therewith, whereupon the lower sash 59 is raised 25 or opened to its ventilating position, as shown by dotted lines in Fig. 9 and full lines in Fig. 10, and if desired the upper sash 60 may also be lowered or opened to its ventilating position shown in 30 full lines in Fig. 10, in which event and at which time the alarm actuating pins 61 and 62 are brought into proximity to the tripping lever 48', and are equi-distant therefrom, so that either of 35 said pins may trip the lever 48' without interfering with the other pin, it being here remembered that the open or ventilating positions of the sashes 59 and 60 herein shown are insufficient to permit anyone entering through the window 57 without actuating the alarm device 20'. In other 40 words, further slight upward or opening movement of the lower sash 59 will cause its pin 61 to contact and trip the lever 48' and thereby release the alarm mechanism, similarly, further slight downward or opening movement of the upper sash 45 60 will cause its pin 62 to contact and trip the lever 48' and thereby also sound an alarm. To reset the alarm device 20' the window sash which actuated the same is returned to its ventilating or closed position, as desired, and the tripping lever 48' returned to its neutral or central position 50 for retripping. However, if deemed expedient the alarm device may be rendered entirely inactive by manipulating the thumb knob 45' to lock the alarm mechanism associated therewith.

Manifestly, therefore, the alarm device of the 55 present invention is extremely simple, compact, durable and economical in construction; is reliable and efficient in operation; will not readily get out of order; and may be rapidly and readily installed.

While, I have herein shown and described the 60 invention with sufficient detail, to enable those skilled in the art to which it pertains, to understand the mode of construction and the principles involved, it is to be understood that there is no 65 intentional limitation herein to the specific forms and precise details of construction shown and described, except as expressly defined by the appended claims, and that various modifications of the same may be resorted to without departing from the spirit of the invention or the benefits 70 derivable therefrom. It is also to be understood that certain features of the invention herein disclosed may be employed in and with combinations other than those shown and described.

What I claim as my invention, and desire to secure by Letters Patent is:—

1. The combination with an alarm device, of an escapement including a rock shaft and a double action pawl, an alarm release dog on said rock shaft, a two-way tripping member adapted when in a normally neutral position to engage either side of said alarm release dog and thereby lock said escapement, and means adapted to move said member in either direction from said neutral position whereby said dog and escapement are released for effecting actuation of the alarm device. 80

2. The combination with an alarm device, of an escapement including a rock shaft and a double action pawl, an alarm release dog on said rock shaft, a two-way oscillative tripping lever adapted when in a normally neutral position to engage either side of said alarm release dog and thereby lock said escapement, and means adapted to move said lever in either direction from said neutral position whereby said dog and escapement are released for effecting actuation of the alarm device. 90

3. The combination with a door, of an alarm device attached to said door and including an escapement, a rock shaft, a double action pawl on said rock shaft adapted to co-act with said escapement, an alarm release dog on said rock shaft, a two-way tripping member adapted when in a normally neutral position to engage either side of said alarm release dog and thereby lock said escapement, and means adapted to move said member in either direction from said neutral position during initial opening movement of said door whereby said dog and escapement are released for effecting actuation of the alarm device. 100

4. The combination with a door, of an alarm device attached to said door and including an escapement, a rock shaft, a double action pawl on said rock shaft adapted to co-act with said escapement, an alarm release dog on said rock shaft, a two-way oscillative tripping lever adapted when in a normally neutral position to engage either side of said alarm release dog and thereby lock said escapement, and means adapted to move said lever in either direction from said neutral position during initial opening movement of said door whereby said dog and escapement are released for effecting actuation of the alarm device. 110

5. The combination with a door and knob thereof, of an alarm device attached to said door and including an escapement, a rock shaft, a double action pawl on said rock shaft adapted to co-act with said escapement, an alarm release dog on said rock shaft, a two-way oscillative tripping lever adapted when in a normally neutral position to engage either side of said alarm release dog and thereby lock said escapement, and means on said knob adapted to move said lever in either direction from said neutral position when said knob is turned in either direction whereby said dog and escapement are released for effecting actuation of the alarm device. 120

6. The combination with a door and knob thereof, of an alarm device attached to said door and including an escapement, a rock shaft, a double action pawl on said rock shaft adapted to co-act with said escapement, a two-way alarm release dog on said rock shaft, a two-way oscillative tripping lever adapted to engage said dog and lock said escapement while in a normally neutral position, and means on said knob adapted to move said lever in either direction from its 130

- neutral position for effecting release of said dog and actuation of the alarm mechanism when said knob is turned in either direction.
7. The combination with a door and knob 5 thereof, of an alarm device attached to said door adjacent said knob, said device having a tripping lever projecting therefrom, and a U-shaped member clamped to said knob and projecting therefrom to receive in spaced relation the outer end 10 of said tripping lever between the legs thereof for effecting tripping of the lever and actuation of the alarm device when the knob is turned in either direction.
8. In combination with the casing and sashes 15 of a window, of an alarm device adapted to be attached to said casing, said device including a two-way tripping lever having a normally neutral position, means on one of said sashes adapted when the sash is opened to move said lever from 20 its neutral position in one direction, and means on the other of said sashes adapted when the sash is opened to move said lever from its neutral position in an opposite direction.
9. In combination with an alarm mechanism, 25 of an escapement including a rock shaft and double action pawl thereon, an arm fixed to said shaft and projecting therefrom, a locking member adapted to engage said arm and lock said escapement, and an alarm release dog on said 30 shaft adapted to lock said escapement independently of said locking member.
10. In combination with an alarm mechanism, of an escapement including a rock shaft and double action pawl thereon, a rigid arm on said 35 rock shaft adapted to project laterally therefrom, a locking member adapted to engage said arm and lock said escapement, an alarm release dog on said shaft adapted to lock said escapement independently of said locking member, and means 40 for stripping said dog to effect release and actuation of the alarm mechanism when said locking member is unlocked.
11. An alarm device comprising a casing, an 45 alarm mechanism enclosed within said casing including an escapement, a rock shaft, a double action pawl on said rock shaft adapted to co-act with said escapement, an alarm release dog on said rock shaft, a two-way tripping lever projecting from said casing and adapted when in a normally neutral position to engage either side of 50 said dog and thereby lock said escapement, and means for moving said lever from its neutral position in either direction whereby said dog and escapement are released for effecting actuation 55 of the alarm mechanism.
12. An alarm device comprising a casing adapted to be attached to a door, an alarm mechanism enclosed within said casing including an escape- 60
- ment, a rock shaft, a double action pawl on said rock shaft adapted to co-act with said escapement, an alarm release dog rigidly mounted upon said rock shaft, a tripping lever adapted to normally engage and lock said release dog while in a neutral position, and means for moving said lever from its neutral position upon opening of the door whereby the dog is released and the alarm mechanism actuated. 65
13. An alarm device comprising a casing, an alarm mechanism enclosed within said casing including an escapement, a rock shaft, a double action pawl rigidly mounted on said rock shaft to co-act with said escapement, an arm similarly mounted on said rock shaft and projecting radially therefrom, a locking member adapted to engage said arm and lock said escapement, a two-way alarm release dog rigidly mounted upon said rock shaft, a two-way tripping lever adapted while in a neutral position to normally engage said dog and lock said escapement independently of said locking member, and means for moving said lever from its neutral position in either direction whereby the dog and escapement are released for effecting actuation of the alarm mechanism when said locking member is also unlocked. 70
14. An alarm mechanism comprising a casing, a spring actuated alarm mechanism disposed within said casing including an escapement, clapper and alarm bell, means for locking said escapement and clapper in an inactive position, an alarm release dog connected to said escapement and clapper, a tripping lever adapted when in a neutral position to engage said dog and lock said escapement and clapper independently of said 75 first mentioned locking means, and means for moving said lever from its neutral position whereby the dog is released and the escapement and clapper actuated to ring the alarm bell when the first mentioned locking means is also unlocked. 80
15. An alarm mechanism comprising a casing, a spring actuated alarm mechanism disposed within said casing including an escapement, clapper and alarm bell, means for locking said escapement and clapper in an inactive position, a two-way alarm release dog connected to said escapement and clapper, a two-way tripping lever adapted when in a neutral position to engage either side of said dog and lock said escapement 85 and clapper independently of said first mentioned locking means, and means for moving said lever from its neutral position in either direction whereby the dog is released and the escapement and clapper actuated to ring said alarm bell when the first mentioned locking means is also unlocked. 90
